ABSTRACT

A partitioning storage rack includes a storage unit that that can store articles. The storage unit includes a plurality of first type storage units that are configured so that one side of the storage unit is visible from the other side, and a second type storage unit that is configured so that the one side of the storage unit is not visible from the other side. The plurality of first type storage units differ from each other in location in the height direction of the partitioning storage rack.

PARTITIONING STORAGE RACK AND BUILDING

TECHNICAL FIELD

The present invention relates to a partitioning storage rack and a building including the partitioning storage rack.

BACKGROUND ART

A known partitioning storage rack partitions a room. For example, Patent Document 1 discloses room dividers (29) arranged between a living room/dining room (9) and a raised floor corner (11). Each room divider (29) is lattice-shaped and includes upright boards (29a) and horizontal boards (29b) coupled together to form three rows and three columns. A backboard (29c) is attached to the lowermost grid row and the middle grid row. No backboard (29c) is coupled to the uppermost grid row.

PRIOR ART DOCUMENTS

Patent Documents

Patent Document 1: Japanese Laid-Open Patent Publication No. 2010-255294

SUMMARY OF THE INVENTION

Problems that the Invention is to Solve

With the above room divider (29), a person in one of the living room/dining room (9) and the raised floor corner (11) can check on the situation of the other one of the living room/dining room (9) and the raised floor corner (11), only by looking through the uppermost grid row of the room divider (29).

Means for Solving the Problems

(1) A partitioning storage rack according to the present invention includes a storage portion that stores an article. The storage portion includes a plurality of first type storage portions configured to allow a person to view through the storage portion from one side to another side and a second type storage portion configured not to allow the person to view through the storage portion from the one side to the other side. The first type storage portions are located at different positions in a height direction of the partitioning storage rack.

With the above partitioning storage rack, the first type storage portions are located at different positions in the height direction. This allows a person in one of two rooms partitioned by the partitioning storage rack to check on the situation of the other room from various positions.

(2) In a preferable example, in the partitioning storage rack described in (1), at least one of the second type storage portion is arranged downward from the first type storage portions in the height direction of the partitioning storage rack.

The above partitioning storage rack has improved rigidity.

(3) In a preferable example, in the partitioning storage rack described in (1) or (2), at least one of the second type

storage portion is arranged upward from the first type storage portions in the height direction of the partitioning storage rack.

The above partitioning storage rack has improved rigidity.

(4) In a preferable example, the partitioning storage rack described in any one of (1) to (3) further includes a plurality of shelf boards arranged in the height direction, a backboard joined with the shelf boards to form the second type storage portion, and a desk joined with the backboard.

10 The above partitioning storage rack has improved convenience.

(5) In a preferable example, in the partitioning storage rack described in (4), the desk is arranged downward from the first type storage portions.

15 With the above building, an object placed on the desk is less likely to be visible from the room that is opposed to one of two rooms including the desk, which are partitioned by the partitioning storage rack.

20 (6) In a preferable example, the partitioning storage rack described in any one of (1) to (5) is configured to be connected to a ceiling and a floor.

25 With the above partitioning storage rack, users of two rooms partitioned by the partitioning storage rack can concentrate on work and still check on each other through the first type storage portions. The users of the two rooms partitioned by the partitioning storage rack can interact with each other at a suitable distance. This provides a comfortable living space.

30 (7) A building according to the present invention includes the partitioning storage rack described in any one of (1) to (6).

35 The above building allows a person in one of two rooms partitioned by the partitioning storage rack to check on the situation of the other room from various positions.

(8) In a preferable example, in the building described in (7), the partitioning storage rack is connected to a floor and a ceiling. The building further includes a first room arranged 40 at one side of the partitioning storage rack and a second room arranged at another side of the partitioning storage rack. The first type storage portions are configured to allow a person in one of the first room and the second room to view the other one of the first room and the second room. The second type storage portion is configured not to allow the person in the one of the first room and the second room to view the other one of the first room and the second room.

45 With the above building, the first room and the second room are partitioned by the partitioning storage rack connected to the floor and the ceiling. Thus, a user of the first room and a user of the second room can concentrate on work and still check on each other through the first type storage portion. The user of the first room and the user of the second room can interact with each other at a suitable distance. This 50 provides a comfortable living space.

55 (9) In a preferable example, in the building described in (8), the second room includes a desk joined with the partitioning storage rack.

The above building improves convenience of the second room.

60 (10) In a preferable example, in the building described in (9), the desk is arranged downward from the first type storage portions.

With the above building, an object placed on the desk is 65 less likely to be visible from the first room.

(11) In a preferable example, in the building described in any one of (8) to (10), the first room includes a kitchen.

With the above building, the user of the first room can check on the situation of the user of the second room through the first type storage portion while doing housework in the kitchen.

(12) In a preferable example, in the building described in any one of (8) to (10), the first room includes an open ceiling structure, and the building further includes a third room arranged upward from the second room and connected to the first room through the open ceiling structure.

With the above building, the user of the first room and a user of the third room can communicate with each other.

Effects of the Invention

The above partitioning storage rack according to the present invention allows a person in one of two rooms partitioned by the partitioning storage rack to check on the situation of the other room from various positions.

BRIEF DESCRIPTION OF THE DRAWINGS

FIG. 1 is a plan view of the first floor of a building including a partitioning storage rack according to an embodiment.

FIG. 2 is a plan view of the second floor of the building.

FIG. 3 is a perspective view of the partitioning storage rack in FIG. 1.

FIG. 4 is a front view of the partitioning storage rack in FIG. 3.

FIG. 5 is a perspective view of a second room in FIG. 1.

FIG. 6 is a cross-sectional view taken along line D6-D6 in FIG. 1.

MODES FOR CARRYING OUT THE INVENTION

Embodiment

An example of a building 10 including a partitioning storage rack 100 will now be described with reference to FIGS. 1 and 2. The example of the building 10 may be a stand-alone house or an apartment house. In the example shown in FIG. 1, the building 10 is a stand-alone house having multiple stories. FIG. 1 is a plan view showing an interior structure 20 of the first floor of the stand-alone house. FIG. 2 is a plan view showing an interior structure 30 of the second floor of the stand-alone house. The building 10 includes outer walls 11 surrounding a region 10A that is divided by walls 12. The region 10A divided by the walls 12 includes an entrance hall 40, an interior space 50, a corridor 60, and stairs 70 as main elements of the interior structures 20 and 30.

The quantities and the layouts of the interior space 50, the corridor 60, and the stairs 70 may be determined in any manner. In one example, the interior space 50 includes a sanitary room 51, a pantry 52, a living room 53, a first meeting room 54, a second meeting room 55, a study room 56, and a master bedroom 57. As shown in FIG. 1, the sanitary room 51, the pantry 52, and the living room 53 are on the first floor of the building 10. The sanitary room 51 includes a lavatory 51A and a bathroom 51B. As shown in FIG. 2, the first meeting room 54, the second meeting room 55, the study room 56, and the master bedroom 57 are on the second floor of the building 10. The master bedroom 57 includes a walk-in closet 57A.

The interior space 50 further includes a first room 81, a second room 82, and a third room 83. As shown in FIG. 1,

the first room 81 and the second room 82 are on the first floor of the building 10. As shown in FIG. 2, the third room 83 is on the second floor of the building 10. The first room 81, the second room 82, and the third room 83 may be of any type. In the example shown in FIG. 1, the first room 81 includes a kitchen 81A and a dining room 81B.

The kitchen 81A is adjacent to the pantry 52. The dining room 81B is connected to the kitchen 81A. There are no walls or the like between the kitchen 81A and the dining room 81B. Thus, a resident who does housework in the kitchen 81A can easily communicate with a user of the dining room 81B. The dining room 81B is connected to the living room 53. There are no walls or the like between the dining room 81B and the living room 53. Thus, a user of the dining room 81B can easily communicate with a user of the living room 53. The second room 82 may be a workroom. Examples of work performed in the workroom are studying and reading. The second room 82 is connected to the first room 81 through an entrance/exit 85. The third room 83 is, for example, a study. The third room 83 is connected to the first room 81 through an open ceiling structure 84 extending from the first room 81. Thus, a user of the first room 81 can communicate with a user of the third room 83.

The stairs 70 are arranged to allow residents to move between the first floor and the second floor of the building 10. The specific structure of the stairs 70 may be determined in any manner. In one example, the stairs 70 are formed in a stairwell. The stairs 70 include a first stair series 71, a second stair series 72, and a landing 73. The landing 73 is arranged between the first stair series 71 and the second stair series 72.

The corridor 60 includes a first corridor 61, a second corridor 62, and a third corridor 63. As shown in FIG. 1, the first corridor 61 and the second corridor 62 are on the first floor of the building 10. The first corridor 61 faces the entrance hall 40, the sanitary room 51, the pantry 52, and the first room 81. The second corridor 62 faces the entrance hall 40, the first stair series 71, the living room 53, and the dining room 81B. As shown in FIG. 2, the third corridor 63 is arranged on the second floor of the building 10. The third corridor 63 faces the first meeting room 54, the second meeting room 55, the study room 56, the second stair series 72, and the master bedroom 57.

The building 10 further includes the partitioning storage rack 100. The partitioning storage rack 100 is arranged between the first room 81 and the second room 82 so that a user of the first room 81 and a user of the second room 82 can interact with each other at a suitable distance. In one example, the partitioning storage rack 100 is connected to a floor 81C and a ceiling 81D (refer to FIG. 3) of the first room 81.

As shown in FIG. 4, the partitioning storage rack 100 includes shelf boards 110, partition boards 120, and back-boards 130 as main elements. The shelf boards 110 are arranged in the height direction of the partitioning storage rack 100 (hereafter referred to as height direction XA). The shelf boards 110 are joined with the wall 12 or the ceiling 81D of the first room 81 (refer to FIG. 3). The partition boards 120 each partition the space between adjacent shelf boards 110 in the height direction XA. The partition boards 120 are joined with adjacent shelf boards 110 in the height direction XA. The space between adjacent shelf boards 110 in the height direction XA is partitioned by the partition boards 120 to form a storage portion 140 that stores articles. The storage portion 140 includes first type storage portions 141 and second type storage portions 142.

The first type storage portions 141 are each configured to allow a person in one of the first room 81 and the second room 82 to view the other one of the first room 81 and the second room 82. In other words, the first type storage portion 141 is configured to allow a person to viewing through the storage portion 140 from one side to the other side. The first type storage portion 141 of the partitioning storage rack 100 does not include the backboard 130. Thus, the first type storage portion 141 allows articles to be stored and removed from both of the first room 81 and the second room 82.

The second type storage portions 142 are each configured not to allow a person in one of the first room 81 and the second room 82 to view the other one of the first room 81 and the second room 82. In other words, the second type storage portion 142 is configured not to allow a person to view through the storage portion 140 from one side to the other side. The second type storage portion 142 of the partitioning storage rack 100 includes the backboard 130. The backboard 130 of each second type storage portion 142 is joined with the side of the shelf boards 110 that is closer to the second room 82. Thus, the second type storage portion 142 allows articles to be stored and removed only from the first room 81.

The quantity of the first type storage portions 141 and the second type storage portions 142 may be determined in any manner. In a preferable example, the quantity of the first type storage portions 141 is less than the quantity of the second type storage portions 142. This improves the rigidity of the partitioning storage rack 100. In the example as shown in FIG. 4, the partitioning storage rack 100 includes 3 first type storage portions 141 and 27 second type storage portions 142.

The first type storage portions 141 are located at different positions in the height direction XA. This allows a person in one of the first room 81 and the second room 82 to check on the situation of the other room from various positions. In the example as shown in FIG. 4, the 3 first type storage portions 141 are located at different positions in the height direction XA.

The layout of the first type storage portions 141 and the second type storage portions 142 may be determined in any manner. In a first preferable example of the layout of the first type storage portions 141 and the second type storage portions 142, at least one of the first type storage portions 141 is arranged downward from the center OA of the partitioning storage rack 100 in the height direction XA. The first type storage portion 141 is arranged at a lower position to allow a person in one of the first room 81 and the second room 82 to check on the situation of the other room in a preferred manner. In a more preferable first example, the first type storage portions 141 are arranged at positions so that a user seated or standing in one of the first room 81 and the second room 82 can view a user seated or standing in the other one of the first room 81 and the second room 82. The user seated in the first room 81 includes at least one of a user seated on the floor 81C of the first room 81 and a user seated on a chair 210 (refer to FIG. 3) in the first room 81. The user seated in the second room 82 includes at least one of a user seated on a floor 82A (refer to FIG. 6) of the second room 82 and a user seated on a chair 220 (refer to FIG. 5) in the second room 82. Regardless of whether the user of the first room 81 and the user of the second room 82 are seated or standing, the user in one of the first room 81 and the second room 82 is allowed to check on the situation of the other room in a preferred manner.

In a second preferable example of the layout of the first type storage portions 141 and the second type storage

portions 142, at least one of the second type storage portions 142 is arranged downward from the first type storage portions 141 in the height direction XA. This improves the rigidity of the partitioning storage rack 100. In a third preferable example of the layout of the first type storage portions 141 and the second type storage portions 142, at least one of the second type storage portions 142 is arranged upward from the first type storage portions 141 in the height direction XA. This improves the rigidity of the partitioning storage rack 100. In a fourth preferable example of the layout of the first type storage portions 141 and the second type storage portions 142, the first type storage portions 141 are arranged at only one side of the center OB of the partitioning storage rack 100 in a width direction XB. In the fourth preferable example, the first type storage portions 141 are not arranged at the other side of the center OB of the partitioning storage rack 100 in the width direction XB.

As shown in FIG. 3, the first room 81 includes a bench 151 joined with the wall 12. In the dining room 81B of the first room 81, a resident may be seated on the bench 151 to relax after finishing a meal.

As shown in FIG. 5, the second room 82 includes a desk 152. This improves the convenience of the second room 82. The relationship between the desk 152 and other elements in the second room 82 may be determined in any manner. In the first example shown in FIG. 5, the desk 152 is joined with the backboard 130 of the partitioning storage rack 100. In the first example, preferably, the desk 152 is arranged downward from the lowest first type storage portion 141 in the height direction XA. Thus, objects placed on the desk 152 are less likely to be visible from the first room 81. One of the user of the first room 81 and a user of the desk 152 in the second room 82 can check on the situation of the other room. In the second example, the desk 152 is separate from the partitioning storage rack 100. The desk 152 may be arranged in any manner in the second room 82. In one example, the desk 152 covers the entire second room 82 in the width direction XB (refer to FIG. 4) of the partitioning storage rack 100. This widens the area of the desk 152 available for use in the second room 82.

As shown in FIG. 6, the third room 83 includes a desk 83A and a chair 83B. This improves the convenience of the third room 83. The relationship between the desk 83A and other elements in the third room 83 may be determined in any manner. In the example shown in FIG. 6, the desk 83A is joined with the backboard 130 of the partitioning storage rack 100.

The partitioning storage rack 100 and the building 10 have the following advantages.

The first room 81 and the second room 82 are partitioned by the partitioning storage rack 100 that is connected to the floor 81C and the ceiling 81D of the first room 81. Thus, users 310A and 310B of the first room 81 and a user 320 of the second room 82 shown in FIG. 6 can concentrate on work and still check on one another through the first type storage portions 141. The users 310A and 310B of the first room 81 and the user 320 of the second room 82 can interact with one other at a suitable distance. This provides a comfortable living space. In one example, the users 310A and 310B of the first room 81 are adults and the user 320 of the second room 82 is a child. In this case, the adult users 310A and 310B can perform work such as housework in the first room 81 and check on the situation of the child user 320 performing work such as homework in the second room 82. Further, the first room 81 is connected to the third room 83 through the open ceiling structure 84 so that a user 33 of the third room 83 is not that visible to the users 310A and 310B

of the first room 81. This protects the privacy of the user 330 of the third room 83 while allowing for communication with the users 310A and 310B of the first room 81. The user 310A of the first room 81 can check on the situation of the user 320 of the second room 82 through the first type storage portion 141 while doing housework in the kitchen 81A.

Modifications

The above embodiment illustrates examples of forms that the partitioning storage rack and the building according to the present disclosure can take and are not intended to limit the forms. The partitioning storage rack and the building according to the present invention may take a form that differs from the forms described in the embodiment. Examples include a form in which part of the configuration of the embodiment is replaced, modified, or removed and a form in which a new configuration is added to the embodiment. One example of modifications of the embodiment will now be described.

The configuration of the partitioning storage rack 100 may be modified in any manner. The partitioning storage rack 100 according to a first modification is configured so that the quantity and the layout of the first type storage portion 141 and the second type storage portion 142 are modified. In the modification, the partitioning storage rack 100 is configured so that the partition boards 120 and the backboards 130 are removable from the shelf boards 110. The partitioning storage rack 100 according to a second modification is not connected to at least one of the floor 81C and the ceiling 81D. In the second modification, when the partitioning storage rack 100 is not connected to the floor 81C or the ceiling 81D, the partitioning storage rack 100 is connected to, for example, the wall 12.

A building including a partitioning storage rack has the following problem.

A known building includes a partitioning storage rack. For example, Japanese Laid-Open Patent Publication No. 2010-255294 discloses the following house (A). The house (A) includes room dividers (29), the living room/dining room (9) arranged at one side of the room dividers (29), and the raised floor corner (11) arranged at the other side of the room dividers (29). With the above house (A), a user standing in the living room/dining room (9) can peep into the raised floor corner (11) from above the room dividers (29). Thus, a user of the raised floor corner (11) may find it difficult to concentrate on work. In this regard, there is room for improvement when providing a comfortable living space. In this respect, the building described below is improved.

Embodiment 1

A building including: a partitioning storage rack connected to a floor and a ceiling; a first room arranged at one side of the partitioning storage rack; and a second room arranged at an other side of the partitioning storage rack, where the partitioning storage rack includes a storage portion that allows for storage of an article, the storage portion includes a first type storage portion configured to allow a person in one of the first room and the second room to view the other one of the first room and the second room and a second type storage portion configured not to allow the person in one of the first room and the second room to view the other one of the first room and the second room.

With the above building, the first room and the second room are partitioned by the partitioning storage rack connected to the floor and the ceiling. Thus, a user of the first room and a user of the second room can concentrate on work

5

and still check on each other through the first type storage portion. The user of the first room and the user of the second room can interact with each other at a suitable distance. This provides a comfortable living space.

Embodiment 2

The building according to embodiment 1, where the first type storage portion is one of a plurality of first type storage portions, and the first type storage portions are located at different positions in a height direction of the partitioning storage rack.

With the above building, a person in one of the first room and the second room is allowed to check on the situation of the other room from various positions.

Embodiment 3

The building according to embodiment 1 or 2, where at least one of the second type storage portion is arranged downward from the first type storage portion in a height direction of the partitioning storage rack.

The above building improves the rigidity of the partitioning storage rack.

Embodiment 4

The building according to any one of embodiments 1 to 3, where at least one of the second type storage portion is arranged upward from the first type storage portion in a height direction of the partitioning storage rack.

The above building improves the rigidity of the partitioning storage rack.

Embodiment 5

The building according to any one of embodiments 1 to 4, further including a desk arranged in the second room, where the desk is joined with the partitioning storage rack.

The above building improves convenience of the second room.

Embodiment 6

The building according to embodiment 5, where the desk is arranged downward from the first type storage portion.

With the above building, an object placed on the desk is less likely to be visible from the first room.

Embodiment 7

The building according to any one of embodiments 1 to 6, where the first room includes a kitchen.

With the above building, the user of the first room can check on the situation of the user of the second room through the first type storage portion while doing housework in the kitchen.

Embodiment 8

The building according to any one of embodiments 1 to 7, where the first room includes an open ceiling structure, and the building further includes a third room arranged upward from the second room and connected to the first room through the open ceiling structure.

With the above building, the user of the first room and a user of the third room can communicate with each other.

60

65

The invention claimed is:

1. A partitioning storage rack, comprising:
a storage portion configured to store an article, wherein
the partitioning storage rack extends in a height direction,
a width direction intersecting the height direction, and
a depth direction intersecting the height direction and
the width direction,
the partitioning storage rack includes a first height part
with a first height and a second height part with a
second height higher than the first height in the height
direction of the partitioning storage rack,
the second height part is laterally connected to the first
height part,
the partitioning storage rack includes a plurality of shelf
boards for storing the article spaced apart by a space
and stackedly arranged in the height direction, wherein
the plurality of shelf boards project in the depth direction
relative to a backboard arranged in the height
direction,
wherein some of the shelf boards are arranged to span
continuously both the first height part and the second
height part,
the storage portion includes a plurality of first type storage
portions configured to allow a person to view through
the storage portion from one side to an other side and
a second type storage portion configured not to allow
the person to view through the storage portion from the
one side to the other side,
the second type storage portion is configured to allow the
article to be stored and removed along the depth
direction, and
the first type storage portions are located at different
positions in a height direction of the partitioning storage
rack.
2. The partitioning storage rack according to claim 1,
wherein at least one of the second type storage portion is
arranged downward from the first type storage portions in
the height direction of the partitioning storage rack.
3. The partitioning storage rack according to claim 1,
wherein at least one of the second type storage portion is
arranged upward from the first type storage portions in
the height direction of the partitioning storage rack.
4. The partitioning storage rack according to claim 1,
further comprising a desk joined with the backboard,
wherein the backboard is joined with the shelf boards to
form the second type storage portion.
5. The partitioning storage rack according to claim 4,
wherein the desk is arranged downward from the first type
storage portions.
6. The partitioning storage rack according to claim 1,
wherein the first height part of the partitioning storage rack
is configured to be connected to a ceiling and a floor, the
ceiling being lower than an upper surface of the second
height part.
7. A building, comprising:
the partitioning storage rack according to claim 1.
8. The building according to claim 7, wherein
the first height part of the partitioning storage rack is
connected to a floor and a ceiling, the ceiling being
lower than an upper surface of the second height part,

the building further comprises:

- a first room arranged at one side of the partitioning
storage rack; and
  - a second room arranged at an other side of the parti-
tioning storage rack,
- the first type storage portions are configured to allow a
person in one of the first room and the second room to
view the other one of the first room and the second
room, and
- the second type storage portion is configured not to allow
the person in the one of the first room and the second
room to view the other one of the first room and the
second room.
9. The building according to claim 8, wherein the second
room includes a desk joined with the partitioning storage
rack.
  10. The building according to claim 9, wherein the desk
is arranged downward from the first type storage portions.
  11. The building according to claim 8, wherein the first
room includes a kitchen.
  12. The building according to claim 8, wherein
the first room includes an open ceiling structure, and
the building further comprises a third room arranged
upward from the second room and connected to the first
room through the open ceiling structure.
  13. The building according to claim 12, wherein
the open ceiling structure is a continuous space extending
across multiple floors, and
each of the first room, the second room and the third room
has a floor and a ceiling.
  14. The partitioning storage rack according to claim 1,
wherein
specific first type storage portions of the first type storage
portions are arranged at positions so that a person in
one of two rooms partitioned by the partitioning storage
rack can view a person in the other one of the two
rooms, and
one of the specific first type storage portions is arranged
to be next to another one of the specific first type
storage portions in the height direction, and is arranged
in a different position from the another one of the
specific first type storage portions in the width direction
of the partitioning storage rack.
  15. The partitioning storage rack according to claim 1,
wherein
at least one of the second type storage portion is arranged
downward from the lowest one of the first type storage
portions in the height direction of the partitioning
storage rack, or
at least one of the second type storage portion is arranged
upward from the highest one of the first type storage
portions in the height direction of the partitioning
storage rack.
  16. The partitioning storage rack according to claim 1,
further comprising a desk joined with the backboard,
wherein
the backboard is joined with the shelf boards to form the
second type storage portion, and wherein the desk is
arranged downward from the lowest one of the first
type storage portions.
